CLAIM

The ornamental design for a faucet mounted water filter, as shown and described.

DESCRIPTION

FIG. 1 is a perspective view of our new design for a faucet mounted water filter;

FIG. 2 is a top plan view thereof;

FIG. 3 is a front elevational view thereof;

FIG. 4 is a right side elevational view thereof;

FIG. 5 is a bottom plan view thereof;

FIG. 6 is a rear elevational view thereof; and,

FIG. 7 is a left side elevational view thereof.

The broken lines showing the adapter nut and water inlet port, the indicator window, the bypass knob, the filter housing release button, the unfiltered water exit port, and the filtered water exit port are for illustrative purposes only and form no part of the claimed design.
